UNITED STATES PATENT OFFICE.

EDWIN E. SLICK, OF WESTMONT BOROUGH, PENNSYLVANIA.

METAL RAILING.

1,241,041.

Specification of Letters Patent. Patented Sept. 25, 1917.

Application filed April 8, 1915. Serial No. 19,893.

To all whom it may concern:

Be it known that I, EDWIN E. SLICK, a citizen of the United States, residing in the borough of Westmont, county of Cambria, 5 and State of Pennsylvania, (whose post-office address is Johnstown, Pennsylvania,) have invented certain new and useful Improvements in Metal Railings; and I do hereby declare the following to be a full, 10 clear, and exact description of the invention, such as will enable others skilled in the art to which it appertains to make and use the same.

My invention relates to metal railings 15 with particular reference to forms which are well adapted for use as bridge railings, inclosures around lawns or gardens, particularly in the city districts, cemetery inclosures, protecting railings along the sides of 20 roads, approaches to bridges and on the tops of retaining walls or embankments, and in fact for use in any location where a strong, neat, substantial and economical railing is desired.

25 A railing, to be of good service, should be of substantial diameter so as to be readily seen and also present to the eye a strong appearance and prior railings of this kind have been made of pipes or tubes, the ends 30 of which are secured together by malleable cast iron or other fittings, either screwed or secured with rivets or dowel pins requiring a multiplicity of connecting pieces of different forms to allow for slopes, corners at 35 different angles, thus requiring base pieces, crosses, T's, ornamental tops of infinite variety of forms which are expensive and difficult to secure and no one railing shop can keep the necessary variety in stock on account of the large number and cost of the 40 same, all of which is obviated by my form of railing which is of substantial appearance, necessary stiffness and strength and economical distribution of material producing 45 lightness, and by reason of its formation and construction is easily made and fitted together without this necessity of the complicated and expensive fittings above referred to.

50 Having thus given a general description of my invention, I will now, in order to make the matter more clear, refer to the annexed sheet of drawings forming a part of this specification and in which like characters of reference refer to like parts:

Figure 1 is a side elevation of a portion of my railing showing one form of the supporting base therefor, when applied to a stone or concrete foundation; Fig. 2 is a transverse sectional elevation taken on the line II—II of Fig. 1; Fig. 3 is a partial side elevation of a portion of the railing showing gusset plate connections between the post and the rails where a stronger and stiffer structure is desired than that illustrated in Fig. 1, and this Fig. 3 also illustrates another method of securing the lower ends of the posts in the concrete or stone foundation; Fig. 4 is a horizontal transverse sectional plan taken on the line IV—IV of Fig. 1 and Fig. 5 is a horizontal transverse sectional plan taken on the line V—V of Fig. 3.

Referring now to the numbers of reference on the drawings: The posts are indicated generally as 1, which are each composed of a hollow cylindrical body portion 2, with an integral flat flange 3, projecting therefrom as shown; angular base brackets 4, are secured to the flanges of the posts 1 by means of the rivets 7, and the railing is secured to the masonry base 5 by means of the anchor bolts 6. As shown in Figs. 1 and 2, the substantially horizontal railing members 9, provided with hollow cylindrical portions 10 and integral flat flanges 11 projecting therefrom, are attached directly to the post flanges 3 by the rivets 8, as shown. The shape and conformation of the rails 9 are similar to those of the posts 1, 80 but may be of smaller size if desired.

Referring now to Fig. 3, a form of post similar to 1 is indicated at 12, this being provided with the hollow cylindrical body portion 13 and a flat integral flange 14 95 projecting therefrom, the lower portion of which flange is shown cut off by a bevel cut 15 so that the lower portion of the post is substantially cylindrical and can therefore be inserted in a round drilled hole or socket 100 16 in the masonry or concrete base. This hole is of slightly larger diameter than the cylindrical portion 13 and after the post is set in said hole it may be poured around with lead, Babbitt metal, sulfur, cement or 105 other material indicated at 17, to hold it securely in place. The rails 18 are provided with the hollow cylindrical portions 19 and with flat integral flanges 20 projecting therefrom, these rails 18 being secured to the 110

posts 12 by means of the gusset plates 21 and the rivets 22, while the gusset plates are secured to the flat portions 14 of the post 12 by means of the rivets 23, all as clearly 5 illustrated.

- A railing of the character shown and described is strong, light and easily assembled, the bars having sufficient dimensions to be readily seen and altogether the construction 10 possesses the advantages that, given the bars themselves, any mechanic can make the railing without the necessity of purchasing a large number of complicated, intricate and expensive fittings.
- 15 A post and railing bar of the formation described can be readily produced in a rolling mill by first rolling a flat bar to the approximate dimensions required and then in the final passes turning over the edge 20 thereof so as to form a substantially cylindrical bead, the edge of the material forming said bead abutting against the flat portion of the bar or adjacent to the junction of the flat portion and the beginning of the curved bead. This bar, therefore, presents the substantial appearance of a pipe and is provided with a flat flange at all places to form connecting means whereby railings, gratings, or other similar structures can be 25 readily fitted and assembled.

Although I have described and illustrated my invention in considerable detail, I do not wish to be limited to the exact and specific details thereof, as shown and described, but 30 may use such modifications in, substitutions for, or equivalents thereof, as are embraced within the scope of my invention, or as pointed out in the claims.

Having thus described my invention, what 40 I claim and desire to secure by Letters Patent is:

1. A railing comprising a plurality of posts each formed with a substantially hollow cylindrical portion, an integral flange 45 projecting therefrom, a railing bar of substantially the same section, the posts and

rails being secured together by means of their flanges.

2. In a railing, a post comprising a hollow cylindrical body portion, an integral 50 flange projecting therefrom, a railing bar of similar section, the two being secured together by means of a rivet or bolt passing through their superposed flanges.

3. In a railing, the combination of a post 55 composed of a hollow cylindrical portion, an integral flange projecting therefrom, a rail of similar section applied thereto with their flanges superposed, and means for securing said flanges together.

4. In a railing, a post having a hollow cylindrical body portion, a flange slightly projecting therefrom, a gusset plate applied and secured to the outer surface of said flange and a railing bar of section similar to 65 the post secured by its flange to said gusset plate, whereby a stiff and strong construction is provided.

5. A railing comprising a post having a body portion of hollow cylindrical form 70 with an integral flange projecting therefrom, the edge of which is parallel thereto, a gusset plate secured to the outside of said flange by means of bolts or rivets, a railing bar of substantially the same shape as the 75 post located at an angle thereto and secured to said gusset plate by means of its flange.

6. A post of hollow cylindrical form with an integral flange projecting slightly therefrom and continuously thereof, a plurality 80 of gusset plates secured to said flat flange, a corresponding plurality of railings located at an angle to said post, said railings having the outer portions of their flanges abutted against and secured to said gusset plates. 85

In witness whereof I have hereunto set my hand in the presence of two witnesses.

EDWIN E. SLICK.
